(57) **CLAIM**

The ornamental design for a handheld power tool housing and handle, as shown and described.

DESCRIPTION

FIG. 1 is a perspective view of an apparatus comprising a handheld power tool housing and handle embodying the ornamental design of the present invention;

FIG. 2 is a side view of the apparatus;

FIG. 3 is an opposite side view of the apparatus;

FIG. 4 is a top view of the apparatus;

FIG. 5 is a bottom view of the apparatus;

FIG. 6 is a front view of the apparatus; and,

FIG. 7 is a rear view of the apparatus.

The broken line showings of FIGS. 1–7 are for illustrative purposes only and form no part of the claimed design.

1 Claim, 3 Drawing Sheets

OTHER PUBLICATIONS

Copies of the front cover, title page and pp. 8, 9, 24 and 25 of a Campbell Hausfeld catalog dated Oct. 1993 and labeled "SL181".

Copies of the front cover and p. 10 of a Chicago Pneumatic catalog dated Aug. 1988 and labeled "75 BP 8/88".

Copy of a 1-page single-sided undated Campbell Hausfeld catalog sheet labeled "High Speed Sander" and "TL1018", no date given.

Copy of a 1-page single-sided undated Campbell Hausfeld catalog sheet labeled "Air Powered Drill" and "TL1006", no date given.

Copy of a 1-page single-sided undated Campbell Hausfeld catalog sheet labeled "Air Chisel" and "TL1003", no date given.

Copy of a 1-page single-sided undated Campbell Hausfeld catalog sheet labeled "Impact Wrench" and "TL1002", no date given.

Copy of a 1-page single-sided undated Campbell Hausfeld catalog sheet labeled "Keyless Chuck Drill" and "PL2545", no date given.

Copy of a 1-page single-sided undated Campbell Hausfeld catalog sheet labeled "Heavy Duty Air Hammer" and "PL2534", no date given.

Copy of a 1-page single-sided undated Campbell Hausfeld catalog sheet labeled "Twin Hammer Impact Wrench" and "PL2502", no date given.

Copy of a 1-page single-sided undated Campbell Hausfeld catalog sheet labeled "Keyless Chuck Reversible Drill" and "PL1545", no date given.

Copy of a 1-page single-sided undated Campbell Hausfeld catalog sheet labeled "Pistol Metal Shear" and "PL1543", no date given.

Copy of a 1-page single-sided undated Campbell Hausfeld catalog sheet labeled "Medium Air Hammer" and "PL1534", no date given.

Copy of a 1-page single-sided undated Campbell Hausfeld catalog sheet labeled "Impact Wrench" and "PL1502", no date given.
